(57) **CLAIM**

The ornamental design for a bracket for mounting component to tablet, as shown and described.

DESCRIPTION

FIG. 1 is a perspective view of a front of an embodiment of a bracket for mounting component to tablet in accordance with the present invention.

FIG. 2 is a front elevational view of the bracket for mounting component to tablet of FIG. 1.

FIG. 3 is a back elevational view of the bracket for mounting component to tablet of FIG. 1.

FIG. 4 is a side elevational view of the bracket for mounting component to tablet of FIG. 1.

FIG. 5 is another side elevational view of the bracket for mounting component to tablet of FIG. 1, which view is opposite to that of FIG. 4.

FIG. 6 is a top view of the bracket for mounting component to tablet of FIG. 1.

FIG. 7 is a bottom view of the bracket for mounting component to tablet of FIG. 1; and,

FIG. 8 is an environmental view showing the bracket for mounting component to tablet and, in particular, showing the bracket mounting a component to a protective case in which the tablet is contained.

Dashed lines shown in the drawings form no part of the claimed design.
